(57) **CLAIM**

We claim the ornamental design for a part of a crimping machine, as shown and described.

DESCRIPTION

FIG. 1 is a left front perspective view of a part of a crimping machine;

FIG. 2 is a left rear perspective view of FIG. 1;

FIG. 3 is a left side elevational view of FIG. 1;

FIG. 4 is a right side elevational view of FIG. 1;

FIG. 5 is a front elevational view of FIG. 1;

FIG. 6 is a rear elevational view of FIG. 1; and,

FIG. 7 is a top plan view of FIG. 1.

The broken lines showing in the drawings are included for the purpose of illustrating portions of the article that form no part of the claimed design.
